RADIO COMMUNICATION SYSTEM

Erich Gessel, Berlin, Germany, assignor to C. Lorenz Aktiengesellschaft, Berlin-Tempelhof, Germany, a company

Application March 31, 1938, Serial No. 199,100
In Germany April 8, 1937

4 Claims. (Cl. 250—11)

The present invention relates to radio communication systems and more particularly to arrangements for effecting directive wireless transmission and reception.

5 It is well known to perform telephonic or telegraphic intelligence communication by means of directive radio systems operating at wavelengths of fractions of meters, for example.

10 The present invention consists in certain features of novelty which will appear from the following description and be pointed out in the appended claims, reference being made to the accompanying drawings, in which:

15 Fig. 1 is a diagrammatic plan of one embodiment of the invention; Fig. 2 is a diagrammatic sectional elevation drawn in a larger scale than Fig. 1 and illustrating the central station of the arrangement; while Fig. 3 is a diagrammatic sectional plan view of the arrangement shown in Fig. 2 and, Fig. 4 shows a modified arrangement at the central station.

20 Referring to Fig. 1, there is shown a central station A being adapted to effect two-way communication with any of the optionally located 25 substations B to G. Each substation has one directive transmitter S and one directive receiver E. The central station A is equipped with the receivers E'b to E'g individually allotted to the corresponding substation. In order to secure 30 two-way communication, it would be necessary also to provide the central station with one particular transmitter for each substation, a requirement which would involve various disadvantages. For instance, if the central station A is placed on a tower at some distance from 35 ground, it will be obvious that the possibility for providing a larger number of transmitters is extraordinarily restricted due to the space conditions prevailing. Moreover, taking under 40 consideration that a plurality of transmitters in close proximity to each other must be operated at wavelengths which differ from one another by a slight amount only, it is evident that interferences between the transmitters will be inevitable 45 during operation.

The present invention has for its object to avoid these difficulties by the provision of a transmitter arrangement in the central station which enables directive communication with each 50 substation with one single directive transmitter only.

According to the invention, the central station is furnished with one particular directive receiver directed toward each substation allotted to the 55 central station, while having one single trans-

mitter common to all substations. The maximum directive radiating characteristic of the transmitter is automatically adjusted toward the substation, the call signal of which has been received in the central station. This problem is 5 suitably solved by the use of a rotatable directive transmitter which is automatically set into the desired direction in response to the receipt of a call signal.

The principle of this proposition is illustrated 10 in Fig. 1, in which the rotatable directive transmitter Sa is automatically turned into the position which corresponds to the direction toward the substation, e. g. the station C, which is assumed to have transmitted a call signal, so as 15 to enable a two-way intelligence transmission between the two stations.

According to a further feature of the invention, wireless two-way connections may be established with substations of particular importance 20 by the agency of specific transmitters in the central station which operate independently of the rotatable main transmitter Sa. This arrangement is illustrated in connection with the substation E of Fig. 1. The central station A is 25 therefore provided with a particular directive transmitter S'e.

Fig. 2 illustrates one embodiment of a wiring diagram of the automatic setting arrangement in the central station A. This figure shows the 30 directive receivers E'g and E'd located in the tower T. The rotatable directive transmitter Sa is placed on a turn-table 1 moved by an electromotor 5 by the aid of the shaft 2 and the bevelled gears 3 and 4. A disc 6, the circumference 35 of which carries a notch, is attached to the shaft 2. One electromagnet 8g and 8d, respectively, is allotted to each substation, and the armatures of these electromagnets are adapted to engage the notch 7 so as to arrest the transmitter in the desired position.

Assuming that the substation G has transmitted a call signal which has been received by the directive receiver E'g of the central station A. The call signal thus received renders the relay Rg effective which closes its contact rg so as to operate the slow-to-release relay Vg which closes its contact vg. This contact remains closed by virtue of the delayed release of this relay even if the call signal from the substation G decays. The operation of relay Vg completes a circuit from the current source 10 over the electromotor 5, the closed contacts kg and vg through the electromagnet 8g back to the current source. The motor 5 is then started and 55

causes the transmitter S_a to rotate until the armature $9g$ of the energized electromagnet $8g$ enters the notch, the transmitter thus being arrested in the desired direction toward the calling transmitter. The armature $9g$ simultaneously opens the contact kg so as to interrupt the energizing circuit for the motor which is then stopped. Meanwhile the slow-to-release relay Vg has restored to normal, so that the contact vg is again open. All switching means operated in the above described cycle are again restored to normal and the transmitter S_a is arrested in the desired direction, so that intelligence exchange may be entered with the substation in question.

15 In addition, means are necessarily provided in the central station so as to prevent movement of the transmitter S_a in response to calling signals from any other substation during the communication with one particular station.

20 Fig. 3 is a horizontal section through the central station A. The directive receivers are denoted $E'b$ to $E'g$. The rotatable directive transmitter S_a has been omitted in this representation for the sake of simplicity. The electromagnets $8g$ to $8b$ are provided for each direction of the substations and that electromagnet is at times energized which pertains to the receiving equipment which has been actuated due to a call signal received. In the case under consideration

25 it is assumed that a call signal has been received by the equipment $E'b$ with the result that the electromagnet $8b$ has been energized and its armature $9b$ has engaged the notch 7 of the disc 2 rigidly attached to the arrangement adapted to move the transmitter. The transmitter is thus arrested in the desired position and the contact kb has been opened. The further circuit elements shown in Fig. 2 have been omitted for the sake of simplicity.

30 40 It is obvious that the desired rotation of the directive radiating characteristic of the transmitter may be attained by other known methods. For instance, a particular directive antenna as shown at $S'b$ to $S'g$ of Fig. 4 may be employed

35 45 for each direction toward a substation. The call signal from such station being adapted to automatically connect the transmitter S_a to the corresponding antenna by means of a rotatable supply switch. This switch may be controlled by the directly received signals in a manner similar to that disclosed above for positioning the reflector shown in Fig. 1.

50 What is claimed is:

55 1. In a two-way directive radio communication system, a central station and a plurality of substations, each substation having one directive transmitter and one directive receiver, the main station comprising a plurality of directive receivers individually directed toward a corresponding

60 65 substation, a rotary adjustable radio transmitter means common to all stations, directive means for directing radiation from said transmitter means selectively toward any of said substations, rotary adjusting means for said trans-

mitter means, means responsive to a call signal received from one substation for energizing said rotary adjusting means to render said transmitter means and said directive means effective in a predetermined direction toward said one substation, and means responsive to the rotary adjustment of said transmitter means to said predetermined position for de-energizing said rotary adjusting means and arresting further rotary movement of said transmitter means.

10 2. In a two-way directive radio communication system, a central station and a plurality of substations, each substation having one directive transmitter and one directive receiver, the central station comprising a plurality of directive receivers individually directed toward a corresponding substation, one directive radiating transmitter common to all substations, a mechanical drive for rotating said directive radiating transmitter continuously in one direction only, a relay arrangement responsive to an incoming call for controlling the rotation of said transmitter, means responsive to operation of said relay arrangement for starting said mechanical drive, and means controlled by said relay arrangement for arresting rotation of said transmitter when the directive radiating characteristic has reached the predetermined direction toward the calling substation.

30 3. In a two-way directive radio communication system, a central station and a plurality of substations, each substation having one directive transmitter and one directive receiver, the main station comprising a plurality of directive receivers individually directed toward a corresponding substation, one rotatable directive transmitting antenna common to all substations, means responsive to a call signal received from one substation for rotating said directive transmitter continuously in one direction only and means responsive to rotary adjustment of said transmitter to a predetermined position aligned with the calling substation for arresting rotary movement of said transmitter.

40 4. In a two-way directive radio communication system, a central station and a plurality of substations, each substation having one directive transmitter and one directive receiver, the main station comprising a plurality of directive receivers individually directed toward a corresponding substation, a plurality of directive antenna arrangements individually allotted to each direction toward a substation, a rotary adjustable transmitter, means responsive to a call signal received from one substation for rotatively adjusting said transmitter for successive cooperation with said directive antenna arrangement and means responsive to adjustment of said transmitter to a predetermined position cooperating with the directive antenna allotted to said one substation for arresting further rotary movement of said transmitter.

ERICH GOSSEL.
